UNITED STATES PATENT OFFICE.

HUNTER DENNIS, OF EXETER, CALIFORNIA, ASSIGNOR OF ONE-THIRD TO ULYSSES GRANT WORLEY, OF EXETER, CALIFORNIA.

MUSIC-LEAF TURNER.

1,125,269.

Specification of Letters Patent.

Patented Jan. 19, 1915.

Application filed February 5, 1914. Serial No. 816,732.

To all whom it may concern:

Be it known that I, HUNTER DENNIS, a citizen of the United States, residing at Exeter, in the county of Tulare and State of California, have invented certain new and useful Improvements in Music-Leaf Turners, of which the following is a specification, reference being had to the accompanying drawings.

10 This invention relates to new and useful improvements in music leaf turners and more particularly to a music leaf turner for application to a piano and the primary object of the invention is to provide a device 15 of this character which will be most efficient in carrying out the purpose for which the same is designed.

A further object of the invention resides in providing a device of this character 20 which is readily operated by the actuation of the foot of the operator and a still further object resides in providing a device which is simple and durable in construction, inexpensive to manufacture and one which 25 will be very efficient and useful in operation.

With these and other objects in view, the invention consists in the novel features of construction, combination and arrangement 30 of parts as will be hereinafter fully described and claimed.

In the accompanying drawings forming a part of this application, Figure 1 is a front elevation of a device constructed in accordance 35 with my invention applied to use on a piano. Fig. 2 is a vertical section through the piano and leaf turner taken on line 2—2, Fig. 1. Fig. 3 is a plan view thereof. Fig. 4 is a detail section as seen on line 4—4, Fig. 40 2, disclosing the lower operating mechanism. Fig. 5 is a detail elevation of one of the supports for the cord guiding mechanism at the top of the piano. Fig. 6 is a similar view partly in section of the upper swinging arm 45 or crane.

In describing my invention, I shall refer to the drawings in which similar reference characters designate corresponding parts throughout the several views and in which—

50 1 designates a piano of the upright type and on the front face thereof above the key board, is mounted a music rack 2. As herein embodied, the rack 2 comprises a skeleton frame 3 of rectangular design which is

hingedly mounted on a shaft or rod, as is believed to be self-evident. 55

My invention primarily contemplates the provision of an improved means for turning the movable frame of the music rack referred to above and, to this end, an arm 5 is 60 mounted for pivotal movement on the top 6 of the piano about centrally of the latter on the forward edge of the same. This arm may, for convenience, be termed a crane and the same is pivotally mounted in a bearing 65 7 provided with bearing balls. The outer end of this arm or crane 5 is provided with a ball or knob 8 designed for engagement with the upper portion of the movable frame 3 of the music rack. Connected to the 70 outer end of this movable arm or crane 5, are the flexible members 9 and 10, which are formed of rope, wire or cable, as desired, and extending in opposite directions. Also 75 mounted on the top 6 of the piano and projecting outwardly therefrom, on opposite sides of the bearing 7, are the stationary arms or supports 11 which are slotted longitudinally and have the flexible members 9 and 10 guided therethrough. Pivoted at 12 80 to the inner ends of the arms 11, are the swinging arms 13 which are adapted to swing through the slots of the arm 11 and the outer ends of these swinging arms 13 are provided with pulleys or rollers 14 over 85 which are trained the flexible members 9 and 10. Thus these swinging arms tend to position the flexible members 9 and 10, so as to readily operate the arms or crane 5 when said flexible members are drawn in one 90 direction or the other. As stated, the flexible members 9 and 10 are guided over the rollers or pulleys 14, at the outer ends of the swinging arm 13 and the same are then directed and guided through openings or 95 channels 15 formed in the top 6 of the piano adjacent the side edges thereof. The openings or channel-ways 15, just referred to, are adjacent the forward edge of the top, outer side of the sounding board 16 of the 100 piano and the flexible connections 9 and 10 which are disposed through said channels or openings are also trained over a plurality of pulleys or rollers 17 arranged in the piano forward of this sounding board. 105 These pulleys are so arranged as to dispose the lower portions of the flexible connections parallel with one another and said connec-

tions are directed to points adjacent the bottom of the piano.

Mounted on the bottom of the piano, just forward of the sounding board, is a supporting post 18 which is slotted at its upper end at 19 and has a somewhat V-shaped crane or arm 20 fulcrumed therebetween, the fulcrum point being indicated at 21. This post 18 is braced by means of a bracing arm 22 and the outer ends of the arm 20 are provided with the adjustable eye bolts 23, the latter being connected with the lower ends of the flexible connections 9 and 10. A pedal member 24 is hinged at its inner end at 25 to the sounding board 16, adjacent the lower edge of the latter, said pedal being disposed through a slot in the front face of the piano adjacent the bottom of the same. This pedal member has a stirrup or U-shaped member 26 secured thereto and is pivoted at 27 to one arm of the V-shaped arm 20. A spring 28 has one end thereof engaged with the bottom of the piano and its other end disposed beneath the pedal to hold the latter normally in its elevated or horizontal position. Thus, it will be seen that when it is desired to turn one of the leaves of the music rack, it is only necessary to press downwardly upon the pedal 24, which operation will rock the member 20 on its fulcrum point on the post 18, and draw upon the flexible member 9. By drawing on this flexible member, the upper crane 5 will be drawn toward the left and carry with it the hinged frame of the music rack. When the foot is released from the pedal 24, the latter will be returned to its initial position under compression of the spring 28 and by the returning of this pedal, the member 20 will also be returned to its initial position to draw upon the flexible connection 10, and drawing of this connection will return the crane or arm 5 to its initial position. It will thus be seen that the frame 3 of the rack may be readily turned by a slight foot actuation of the pedal 24.

From the foregoing description of the construction of my improved device, the manner of applying the same to use and the operation thereof will be readily understood and it will be seen that I have provided a device which is simple and durable in construction, inexpensive to manufacture and one which will be very efficient and useful in operation.

While I have particularly described the elements best adapted to perform the functions set forth, it is obvious that various changes in form, proportion and in the minor details of construction may be resorted

to without departing from the spirit or sacrificing any of the principles of the invention.

Having thus described this invention, what I claim is:—

1. In a music leaf turner, the combination with a support, and a swinging frame carried thereon adapted to receive sheets of music thereon; of an arm pivotally carried on the top of said support and projecting outwardly therefrom, said arm being adapted for engagement with the swinging frame to turn the latter at predetermined times, stationary arms projecting outwardly from the support, said arms being provided with longitudinal slots, additional arms pivotally carried by the stationary arms and movable through the slots thereof, pulleys carried on the outer ends of said last named arms, flexible connections engaged with said first mentioned arm and extended in opposite directions therefrom, said flexible connections being also trained over the pulleys, and means engaged with the ends of said flexible connections for drawing upon the latter and correspondingly actuating said first mentioned arm whereby to actuate said swinging frame.

2. In a music leaf turner, the combination with a support, a swinging arm carried thereon, and flexible connections engaged with said swinging arm to actuate the latter upon the actuation of said flexible connections, said flexible connections being guided on the support at points adjacent the bottom of the latter; of a supporting post mounted on the bottom of said supporting member and having the upper end thereof bifurcated, an arm fulcrumed intermediate of its ends in the bifurcated end of said post, means engaged with the outer ends of said arm for adjustably connecting the lower ends of said flexible connections thereto, a pedal member hinged at its inner end on said support, below said fulcrum arm, means for connecting said pedal member to one extension of said fulcrum arm to actuate the latter upon the actuation of the pedal member, and spring means in connection with said pedal member and the bottom of said support to normally dispose said pedal member and parts carried thereby in a predetermined position.

In testimony whereof I hereunto affix my signature in the presence of two witnesses.

HUNTER DENNIS.
